UNITED STATES PATENT OFFICE

JULIUS STEINMETZ, OF WINTHROP, MASSACHUSETTS

SIGN

Application filed December 24, 1931. Serial No. 583,009.

This invention relates to signs, and more particularly to an illuminated advertising sign.

At the present time it is a common practice to place signs in the front windows of restaurants, stores and the like which advertise certain articles, quote prices and give other information, and to make such signs attractive they are illuminated. These signs usually have a wooden frame surrounding them or no frame at all, and in cases where the sign has an ornamental frame or border it is not illuminated because the material is not capable of transmitting light. Also the advertising portion of the sign presents a flat or at least unornamental surface because the glass or other materials now used to make such signs cannot be moulded or made with depressions and projections which are necessary in order to achieve real ornamentation in the advertising portion.

One object of my invention is to provide a new illuminated sign the whole front of which is lighted, making a variety of colors possible. Another object has been to provide such a sign with an illuminated border or frame. Still another object has been to so make such a sign that it can be made of inexpensive material at a low labor cost and of such simple construction that it may be sold at prices which meet the competition of inferior signs.

The foregoing and other objects which will appear as the nature of the invention is better understood, may be accomplished by a construction, combination and arrangement of parts such as is disclosed by the drawings. The nature of the invention is such as to render it susceptible to various changes and modifications, and, therefore, I am not to be limited to the construction disclosed by the drawings; but am entitled to all such changes therefrom as fall within the scope of my claims.

In the drawings:

Figure 1 is a front elevation of my sign showing a projecting border around the advertising portion surrounded by an outside frame.

Figure 2 is a cross-section on the line 2—2 of Figure 1.

Figure 3 is a reduced plan view of my sign.

Figure 4 is a detail view of the stand or easel which supports my sign, looking in the direction of the arrow A.

As illustrated my sign has a casing or supporting member 12, the sides of which converge towards the rear as shown, the inside of which may serve as a reflector by painting it white, nickelizing it or otherwise providing a reflecting surface. Vent holes 13 are provided as a precaution to permit the escape of heated air. At the rear of said casing 12 is an opening 14 having a removable cover 15 which may be sprung into place. Within said casing is a standard electric lamp 16 with cord 17 attached to connect with any suitable source of electric current, not shown.

My sign may be supported in an upright position by an easel 20 riveted as at 22 to said casing 12, which easel has two legs or pieces of sheet metal 21, the lower one having a longitudinal slot 23 to make said easel adjustable, and the upper leg having a hole 24. A bolt 25 passes through said slot 23 and hole 24 and has a wing nut 26 to hold it fast in any desired position in said slot 23. My sign is adapted to be suspended or hung up as well, either indoors or outdoors, in which event no easel is necessary.

A front or face 28 may be made all in one piece of some kind of screening. I have found fourteen mesh galvanized wire screening suitable for this purpose, and this whole front 28 may be stamped out of a single piece of material including the outside portion or frame 29 which surrounds the inner or advertising portion 30. Said screening is dipped in, or the openings in the mesh are otherwise covered, with a transparent or light trans-

mitting material, such as nitro-cellulose la-
quer for instance, after being stamped or
otherwise formed to the desired shape. In
order to make said front 28 as ornamental and
attractive as possible it has depressions and
projections formed in it, some of which are
designed to serve a useful purpose. For in-
stance, depressions 31 receive holders 33
which extend across the advertising portion
30 at the front of the screening, which holders
have slots 34 adapted to receive flexible sym-
bolic members 35, such as letters, figures or
symbols, which may be sprung into said slots
34. It should be noted that the portions of
said front 28 on which said symbolic mem-
bers 35 rest are arched, causing the letters to
stand out prominently and making the read-
ing or advertising portion 30 of said sign
much more attractive than if it were flat as
would be necessary were it made of glass.

The shape of an insignia may be stamped into said front 28 by making the proper depressions or projections, or both, in said front, and suitably coloring it. In this event the letters or symbols 35 as well as the holders 33 may be omitted.

Said holders 33 have countersunk holes through which bolts 36 extend from the front to the rear of the screening where there is a washer 37 at the end of the bolt, and a nut 38, which elements fasten said holders 33 in place on said front 28.

35 Said front 28 is lapped over along its outside edge, and is bolted as at 40 to said casing 12. Said outside frame 29 may be of any configuration or its outside edges may be straight and the casing 12 should correspond in shape to it at the point where it is riveted so that the whole front 28 will be illuminated.

40 Surrounding the advertising portion 30 of
my sign all the way around is what appears
from a front view to be a tubular rim 42
which is formed by merely projecting a por-
tion of said front 28, illustrated in the cross-
45 section (Figure 2) of the drawings. Said
projecting portion when painted or otherwise
colored red or some other color than the rest
of the front, has the appearance of a neon tube
and enhances the beauty of my sign.

50 What I claim is:

1. A sign comprising a supporting member, a lighting means mounted in said member, a front attached to said supporting member, said front being formed of screening the openings in which being covered with a light transmitting material, said front embodying an advertising portion and an outside frame portion, said advertising portion having depressions therein, holding members in said depressions fastened to said front and having provision to receive symbolic members between them.

2. A sign comprising a casing, lighting means in said casing, a front attached at approximately its outside edge to said casing

c-said front being formed of open mesh material and having said openings covered with a light transmitting material, said front having depressions formed therein, holding members in said depressions fastened to said front having provision to receive symbolic members, said front embodying an advertising portion, a projecting portion bordering said advertising portion, and a frame portion surrounding said border.

3. A sign comprising a casing, lighting means in said casing, a front attached at approximately its outside edge to said casing, said front being formed of one piece of screening the openings being covered with a light transmitting material, said front embodying an advertising portion, a projecting border portion surrounding said advertising portion, and a frame portion surrounding said border, said advertising portion having depressions therein, holding members in said depressions fastened to said front and having provision to receive symbolic members between them, the portions of said advertising portion between said holding members being arch-shaped. 80 85 90

4. A sign comprising a casing, lighting means in said casing, a front attached to said casing, said front being formed of open mesh material the openings being covered with a light transmitting material, said front embodying an advertising portion having projections therein extending horizontally and spaced apart, holding members in said depressions having slots therein adapted to receive symbolic members, the portions of said advertising portion between said projections being arch-shaped, said front having a projecting border portion surrounding said advertising portion and a frame portion surrounding said border. 100 105 95

5. A sign comprising a supporting member, lighting means, a front formed of open mesh material attached to said member and forward of said means, said front having portions projected and depressed from the plane surface and having the openings covered by a light transmitting material, said projected portions forming surfaces for symbolic members, and means in said depressed portions to hold said members on said surfaces. 115

JULIUS STEINMETZ.
